CLAIM

The ornamental design for a game board, as shown and described.

DESCRIPTION

FIG. 1 is a perspective view of the game board; FIG. 2 is a top plan view of the game board; FIG. 3 is a bottom plan view of the game board; FIG. 4 is a left side elevational view of the game board; FIG. 5 is a right-side elevational view of the game board; FIG. 6 is a rear elevation view of the game board; and, FIG. 7 is a front elevation view of the game board. The broken lines showing elements of the article illustrate portions of the game board that form no part of the claimed design.

1 Claim, 5 Drawing Sheets
